UNITED STATES PATENT OFFICE.

DANIEL C. WILGUS, OF LOS ANGELES, CALIFORNIA.

DESIGN FOR A NOZZLE FOR LAWN-SPRINKLERS.

SPECIFICATION forming part of Design No. 23,700, dated October 16, 1894.

Application filed August 29, 1894. Serial No. 521,644. Term of patent 7 years.

To all whom it may concern:

Be it known that I, DANIEL C. WILGUS, a citizen of the United States of America, residing at Los Angeles, in the county of Los Angeles and State of California, have invented a new and original Design for a Nozzle for Lawn-Sprinklers, of which the following is a specification, reference being had therein to the accompanying drawings.

10 This invention relates to a certain new and useful design of nozzle for a water sprinkler.

The peculiar shape and configuration of the new and ornamental design of nozzle for a water sprinkler are more fully and particu-

15 larly described and pointed out hereinafter.

Referring to the accompanying drawings, Figure 1, is a top plan view of the new design of nozzle for a water sprinkler. Fig. 2, is a side elevation of the same.

20 The new design of nozzle for a water sprink-

ler or sprayer consists of the round flat body, *a*, having the substantially flat bottom, *b*, and the convexed or upwardly rounded top, *c*, provided with the round central aperture, *d*. *c*, are lateral lugs from the edge of said body ²⁵ *e*, preferably from the lower portion of the edge. *f*, is a neck extending tangentially from the edge of said body as clearly shown and having the open end.

Having thus fully described my invention, ³⁰ what I claim as new, and desire to secure by Letters Patent of the United States, is—

The design for a nozzle for a water sprinkler substantially as herein set forth and shown.

In testimony whereof I affix my signature in ³⁵ presence of two witnesses.

DANIEL C. WILGUS.
